JOSEPH SHEBOL AND WILLIAM F. ALBRECHT, OF SYRACUSE, NEW YORK.

FLUID-PRESSURE GAGE.

1,002,877.

Specification of Letters Patent. Patented Sept. 12, 1911.

Application filed August 25, 1910. Serial No. 578,942.

To all whom it may concern:

Be it known that we, JOSEPH SHEBOL and WILLIAM F. ALBRECHT, of Syracuse, in the county of Onondaga, in the State of New York, have invented new and useful Improvements in Fluid-Pressure Gages, of which the following, taken in connection with the accompanying drawings, is a full, clear, and exact description.

10 This invention relates to certain improvements in fluid pressure gages involving the use of a tubular spring sector contracting under its own tension and having one end receiving the fluid under pressure and its other end closed and free to move or expand under such pressure and connected to a suitable indicating mechanism for registering the degree of pressure of the fluid.

The main object is to establish as nearly 20 as possible a direct connection between the movable end of the tubular sector and index finger for the purpose of reducing the number of parts and the cost of manufacturing and at the same time simplifying the assembly and adjustment.

Another object is to enable the index finger to be easily and quickly adjusted with reference to the graduations on the dial without loosening any of the connections 30 between the spring sector and finger thereby maintaining a positive connection and reducing the liability of the index finger becoming displaced when the instrument is once adjusted.

35 A further object is to enable the entire mechanism exclusive of the case to be assembled as a unit and properly adjusted before being inserted into the said case and to utilize a portion of the main supporting post 40 for the spring, dial and other operating parts for the reception of a wrench whereby the entire indicator including the case may be readily attached or screwed upon a pressure producing device or other part connected thereto without liability of overstraining the case or any part of the mechanism.

A still further object is to secure the dial 50 to the post eccentrically so that when inserted in the case it will be self retaining against circumferential displacement.

Other objects and uses will be brought out in the following description.

In the drawings, Figure —1— is a front 55 elevation of the complete indicator. Fig.

—2— is a similar elevation except that the cap of the case is removed to show the interior mechanism. Fig. —3— is a rear view of the same device showing a portion of the post, spring sector and case in section. Fig. —4— is a side elevation of the interior mechanism showing the case in section. Fig. —5— is an enlarged front elevation of a portion of the interior mechanism showing particularly the connections between the index finger and movable end of the spring sector. Figs. —6— and —7— are sectional views taken respectively on lines 6—6 and 7—7, Fig. 5. Fig. —8— is a side elevation partly in section similar to Fig. —4— showing a modified form of post and attaching nipple secured thereto and projecting through the back of the case.

This gage is adapted more particularly for indicating the degree of air pressure for 75 pneumatic tires and similar uses and comprises a main supporting post —1— carrying a spring sector —2— and dial —3— and an index finger —4— which is connected by a link —5— to the free end of the spring 80 sector —2—, the entire mechanism thus far described being mounted within a suitable case —6—.

The post —1— is preferably square in cross section and provided with an integral 85 threaded nipple —7— which together with the adjacent square portion of the post is adapted to be inserted through a square opening —8— extending radially through one side of the case so as to leave one end of 90 the square portion of said post projecting some distance from and beyond the periphery of the case for the reception of a wrench whereby the entire indicator may be readily screwed to a pressure generator not 95 shown or any attachment thereof. The threaded end of the post is provided with a central opening or passage —9— communicating with one end of the flat tubular spring sector having one end inserted in a 100 groove or slot —10— in one side of the square portion of the post —1— and rigidly secured therein by soldering or otherwise, the other end being closed and extending around the upper end of the post some distance 105 therefrom and to the opposite side thereof so as to be free to expand and contract under varying pressures of the fluid which may enter the sector. The radius of the spring sector —2— is somewhat less than 110

that of the interior of the case within which it is located so as to allow ample clearance for the free movement thereof under its own tension and under varying pressures of the operating fluid.

5 The dial —3— is nearly semi-circular and of a radius substantially equal to that of the interior of the case with which its periphery is adapted to closely fit when adjusted for use, said dial being eccentrically secured to the front side of the post —1— by suitable fastening means as a single screw —11— and interposed washer —12— so that when the post or the dial thereon is placed 10 within the case engagement of the periphery thereof with the interior of the case will prevent rotary displacement of the dial thereby assuring proper relations between the dial and index finger. The object of the washer —12— is to hold the dial clear 15 from the spring sector and other movable parts lying directly under the same, said dial being provided with the usual graduations numbered in this instance from zero to 150 degrees and extending through an arc of about 90 degrees concentric with the axis movement of the index finger —4—. This index finger —4— is pivoted directly to the front side of the post —1— by a pivotal screw —13— in proximity to the point of 20 securement of the spring sector —2— so as to travel freely around the dial and is provided with an integral arm —14— see Fig. 6 projecting from the hub thereof and bent 25 or returned upon itself into the form of a loop. The free end of this arm or loop terminates at one side of the pivotal screw —13— and between said pivotal screw and dial and is connected by the link —5— to a 30 bendable arm or extension —16— on the free end of the spring sector —2— thereby forming a nearly direct and positive connection between said sector and index finger, the link extending in this instance across the arc of 35 movement or near the axis of said index finger so as to operate the finger from its normal position at its zero point at the left along the graduations under fluid pressure acting upon the sector. The object in bending 40 the pendant arm or extension —14— of the index finger into the form of a loop is to permit the free end of said arm to be adjusted toward and from the fulcrum or pivot —13— when necessary to properly 45 adjust the index finger with reference to the dial. That is, if the index finger does not register with the proper graduation on the dial under predetermined pressure in the 50 spring sector, the arm —14— may be bent or twisted laterally by a pair of pincers or other suitable tool until the index finger is brought to the proper graduation. One end of the extension —16— is inserted into the free end 55 of the tubular sector —2— and is secured 60

therein by soldering or otherwise to effectively close or plug this end of the sector, the remaining portion of the arm —16— is comparatively narrow so it can be readily bent by a pair of pincers or similar tool 70 for the purpose of additionally adjusting the index finger. That is, it may be adjusted toward and from the free end of the sector to vary the speed of movement or throw of the index finger or it may be adjusted laterally with reference to the axis of movement of the finger to bring such finger into registration with the proper graduation under a predetermined fluid pressure in the sector.

75 In some instances, it may be necessary or desirable to attach the instrument at the back to the pressure device or other attachment and in Fig. —8— we have shown the post as made in two sections —20— and —21—, the section —20— carrying the sector, dial, index finger and other active parts of the device being located within the case —6— and provided with a suitable aperture in the back side thereof for the reception of one end of section —21— which is passed 90 through an opening in the back of the case and secured into the inner post section. The section —21— is provided with a square portion and also with a hollow threaded nipple, the square portion serving to receive 95 a wrench or similar device whereby the indicator may be secured upon a pressure device not shown. The opposite ends of the link —5— are pivotally connected by suitable screws to the corresponding ends of the adjusting arms —14— and —16— of the index finger —4— and sector —2— respectively.

100 In the preferred form of our invention shown particularly in Figs. —1—, —2— and —3— the post —1— is secured against the interior of the back of the case by fastening screws —1'— see Fig. 4. The front of the case is provided with a suitable cap —6'— removably secured thereto by screws —7'— and provided with sight opening —22— 105 across which is placed a transparent shield —23—, the sight opening conforming nearly to the shape of the dial or rather to the arc of the graduations so that the corresponding end of the index finger and graduations may be always visible through the transparent shield. This shield serves to prevent the entrance of dust to the interior of the case through the sight opening and is held in place by an inner apertured plate —24— 110 which is secured by one or more rivets —25— to the front of the cover.

115 What we claim is:

120 1. In a fluid pressure gage, a tubular spring sector, and a support therefor having an inlet passage communicating with one end of the sector, an index finger having a hub pivoted to the post, said hub provided with a bendable arm having its free end 125 bendable toward said arm extending across 130

the hub, and from the axis of the pivot and connections between the free end of the sector and arm.

2. In a fluid pressure gage, a post having an inlet passage, a hollow spring sector having one end secured to the post and communicating with said passage and its other end free to move relatively to the post, an index finger having a hub pivoted to the post, said hub provided with an arm overlapping the hub and bendable toward and from the pivotal axis of the hub and connections between the closed end of the spring sector and free end of the arm, said connections extending across the hub.

3. In a fluid pressure gage, a post having an inlet passage, a hollow spring sector having one end secured to the post and communicating with said passage and its other end closed and movable relatively to the post, an extension on the closed end of the sector and bendable relatively thereto, an index finger having a bendable extension and connections between the said bendable extensions.

4. In a fluid pressure gage, a post having an inlet passage, a hollow spring sector hav-

ing one end secured to one side of the post and communicating with said passage and its other end closed and free to move relatively to the post and a bendable extension on the closed end of the sector, an index finger having one end pivoted to the post and provided with an extension bendable toward and from its axis of movement and projecting across the pivoted end of said finger and a link extending across the pivoted end of said finger and connecting the bendable extension of the sector to the bendable extension of the index finger.

5. In a fluid pressure gage, a pivoted index finger having an extension overlapping its pivoted portion and bendable toward and from its axis of movement, a fluid pressure operated means connected to said extension for operating the index finger.

In witness whereof we have hereunto set our hands on this 19th day of August, 1910.

JOSEPH SHEBOL.
